UNITED STATES PATENT OFFICE.

MAX EMILIUS MILLWOOD, OF EDMONTON, ALBERTA, CANADA.

SUCTION PROPELLING MEANS.

Application filed July 22, 1924. Serial No. 727,507.

To all whom it may concern:

Be it known that I, MAX EMILIUS MILLWOOD, a subject of the King of Great Britain, and resident of the city of Edmonton, 5 in the Province of Alberta and Dominion of Canada, have invented certain new and useful Improvements in Suction Propelling Means, of which the following is a specification.

10 This invention relates to improvements in suction propelling means, and the objects of the invention are to provide improved means of this character particularly adapted for aeroplanes, airships and the like, but 15 which can also be applied with most satisfactory results to motor driven vehicles and machinery of all kinds.

In the example of my invention herein-after more fully described and illustrated, 20 it is shown as applied to an aeroplane to propel it, to cause it to rise vertically, to travel horizontally when required, and to descend vertically.

The advantages thus obtained over anything of the kind at present in use will be 25 apparent. I am aware that many attempts have been and are still being made to solve the problem of providing an aeroplane that can ascend and descend vertically, and that 30 for this purpose the helicopter idea appears to be the one on which others have concentrated. With my improved suction-operated propeller, however, the difficulties experienced with the helicopter idea would be 35 overcome and it will be possible to more efficiently perform the functions of a helicopter as well as those of an ordinary plane. Furthermore, the construction involved is 40 simple, durable and more economical than that at present employed.

A further and essential object of my invention is the provision of means for operating propellers and the like by suction 45 which can be adapted to practically all mechanisms in which motor power is used.

With the foregoing and other objects in view hereinafter more fully explained, my invention consists essentially in the combination 50 with an engine or motor having a suitable housing provided with air intake conduits and discharge opening, of a plurality of specially designed propeller blades driven

by said motor and having therebetween specially formed and fixedly mounted baffles whereby, on the propellers being operated, 55 the air is sucked into and through the housing to be checked in its rush by said baffles, thus providing first a vacuum within the housing and then an accumulation of air under pressure available for the propeller 60 blades to grip, as it were.

From the foregoing, it will be seen that my idea and means for carrying it out are, to all intents and purposes, directly the opposite to those at present in use, in that with 65 my improved construction the propellers, instead of, as at present, operating in the open air or water as the case may be, may operate within the casing in combination with baffles, and that the air contacting with 70 the propeller blades is concentrated or compressed for the moment, thus providing a compression chamber, in combination with baffles, in which the air for the propellers is concentrated, thus producing on each rotation of the propeller blades in the compressed air far greater power than could be attained by the propellers rotating in the 75 open air.

In short, the essential object and idea of 80 my invention is the provision in a practical manner and in a convenient form of means for first compressing air and then using the compressed air for driving or propelling purposes by means of propeller blades in 85 combination with suitable baffles.

Furthermore, with my improved means 90 an air-cooled engine can be used with greater advantage than a water-cooled engine and with, as is well known, much less expense 95 and at the same time greater efficiency, as once the air has passed through the baffles it rushes to the exhaust, the mechanism casing being open at the end, and in so doing provides a current of air surrounding the 95 engine to automatically and continuously cool it.

A still further feature of my invention is the construction of the propeller blades formed, in combination with the hub, in two 100 sections, and bent in a particular manner and of substantially spoon-shaped formation.

The curved formation of the baffle blades

is also a feature and enables them to direct the current of air inwardly towards the hub or centre, thus exerting pressure at the strongest resistant point of the machine.

5 These baffle blades are spaced apart at distances corresponding to the width of each of the blades.

Another feature of my improved construction is the reduction of engine speed, 10 at the same time giving more satisfactory results, thus reducing wear and tear and running costs.

Referring now to the drawings, in which like characters of reference indicate corresponding parts in each figure:

15 Figure 1 is a plan view of an aeroplane fitted with my improved suction propelling means.

Figure 2 is a front elevation.

20 Figure 3 is a longitudinal vertical section through the shell or casing containing the propeller mechanism.

Figure 4 is a face view of the baffles and propellers.

25 Figure 5 is a similar view of the baffles.

Figure 6 is a section on line 6—6 of Figure 4 showing the staggered arrangement of the propeller blades.

30 Figure 7 is a plan view of the mechanism for operating the air intake.

Figure 8 is a sectional detail of the aeroplane wing.

Figure 9 is a perspective detail of the air conduit sleeve for said wing.

35 Figure 10 is a perspective detail of the propeller blade.

Figure 11 is a sectional detail showing the manner of fitting the blades to the hub.

40 Referring now more particularly to the drawings, in the example of my invention here shown as applied to an aeroplane, A designates an aeroplane comprising the wing 10, body 11, tail 12, and steering mechanism 13. In the position usually occupied 45 by the propeller is a casing or shell 14. This casing, in combination with suitable intake and discharge air conduits in the machine hereinafter more fully described, is adapted to house the engine 15 provided with a driving shaft 16 mounted in ball-bearings 17 in the casing.

45 Referring now more particularly to the casing or shell as illustrated in Figure 3, this is here shown as substantially dome-shaped and is formed with channels or conduits 18 and 19 extending longitudinally from adjacent the base towards the front and formed at their front ends with openings 18^a and 19^a communicating with the hollow head 46 in the nose of the casing or shell 14. In spaced relationship to these channels are similarly formed shorter channels or conduits 20 and 21 in the shell having openings 20^a and 21^a at their inner ends 50 also communicating with the hollow head

46. It will thus be seen that the channels 18 and 19, in combination with the channels 20 and 21 formed in the shell, are so arranged as to convey an even supply of air in operation to the hollow head 46. In other words, the member 14 is practically a double shell, the air conduits or channels forming the division between the outer shell portion 14^a and the inner channel portion 14^b. The other ends of these channels or 55 conduits 20 and 21 are connected by means of conduits or pipes 30 and 31 with air intake openings 28 and 29 in the front of the wing 10, while the channels or conduits 18 and 19 of the shell are connected at their 60 inner ends through conduits or pipes 26 and 27 with the air intake openings 22 and 23 in the top of the wing 10. These wing openings are designed to form air intakes, the conduits 18 and 19 communicating with 65 openings 22 and 23 being used when it is desired to propel the machine vertically upwards and then, on assuming a required position, the openings 22 and 23 are closed and the openings 28 and 29 in the wing are 70 opened to cause the machine to travel in a horizontal direction. When it is desired to descend, the openings 22 and 23 are opened and the openings 28 and 29 are closed. In connection with these air intakes rotatably 75 mounted on the shaft 16 are the propellers 32 comprising four blades of special spoon-shaped formation, as illustrated in Figure 10, and provided with openings 36 in the squared inner ends 37 whereby they are connected to the hub 38. It will also be noted that they are made in two sections and that when assembled they will be in staggered 80 relationship, as shown in Figure 6.

85 It should also be noted that I provide, as illustrated in Figure 8, a partitioning directing member 67 to be used in connection with the air intakes 28 and 29 in the front of the wings, so as to cause the air rushing in to be spread and thus to evenly enter the 90 conduits 20 and 21 on their way to the chamber 46.

95 Mounted in the casing and provided with a hub 38 provided with ball bearings 39 for the shaft 16 to rotate in is the baffle carrying member 40 (see Figures 3, 4 and 5). This member comprises a plurality of spaced and curved baffles or blades 42 fixedly connected to an outer rim 43 at one 100 end and to the hub 38 at the other end and curved inwardly towards the bottom to concentrate on the hub or centre the pressure of the air. The baffles 42 are spaced from one another by spaces 44 corresponding in width to that of a propeller blade. The 105 curved formation of these baffles is designed to scoop, as it were, the air so as to automatically conduct it inwardly towards the centre. The rims 43 of the baffles are preferably, as here shown, hinged at 45. 110

From the foregoing it will be gathered as the propeller blades 32 rotate and openings, say 28 and 29, are opened in the wing 10, that the air will be sucked in through the 5 conduits 30 and 31 and, as indicated by the arrows, into the space 46 in the head of the casing or shell 14, and in which a vacuum is momentarily formed by the rotation of said blades. Almost at the same time the 10 air so drawn in comes in contact with the baffles between the propellers causing it, as previously explained, to be directed downwardly to the centre under pressure, thus forming, as it were a pocket of compressed 15 air to contact with the rotating propeller blades and to be gripped by them as they rotate in the staggered relationship, as illustrated in Figure 6. After passing through the baffles the air then passes through the 20 second propeller, and then finally it is discharged through the open discharge 47 of the shell, having between the propellers and said opening or exhaust automatically cooled the engine 15 in its travel.

25 Referring now more particularly to the air intake openings and the conduits, the mechanism for opening and closing the air intakes 22 and 23 in the top of the wing and 28 and 29 in the front of the wing is 30 illustrated in Figures 7, 8 and 9 and consists of a longitudinally extending shaft 48 provided with an operating handle 49 at its inner end within reach of the pilot of the machine. This shaft 48 is provided 35 with a worm 50 adapted to mesh with a worm gear on a transversely extending shaft 52 provided with gears 53 and 54 at each end adapted to operate the shutters or valves for opening and closing the openings 22 and 23. A second worm 55 is also provided on the shaft 48 designed to mesh with a gear 56 on a transversely extending shaft 57 parallel with the shaft 52. This shaft 57 carries sleeve members 58 at each 40 end and is also provided with a gear 59 adapted to mesh with a gear 60 and a gear rod 60^a. These sleeves are designed to fit into the wings and to rotate therein, on the shafts 57 being operated. The sleeve members 58 are provided with a longitudinal 45 opening 61 so that when rotated to open the intakes 28 and 29 the opening 61 in the sleeve will register therewith, and vice versa. The body of the sleeve when further rotated will form a closure or shutter for the openings 28 and 29.

50 This shaft 52 is arranged to operate at each end, similar to the shafts 57, and it will be seen that, on the operating wheel 60 49 being turned and the shaft 52 operated to open the top openings 22 and 23 in the wing 10, simultaneously with this operation the shafts 57 will be operated to close the air intakes 28 and 29 so that only one 55 set of these intakes will be open at any time, as before explained. The top intakes 22 and 23 are opened when it is required to raise the machine vertically, the air then being sucked in through the conduits 18 and 19 in the shell and travelling, as indicated by the arrows, into the chamber 46. Then, on the intakes 22 and 23 being closed to cause the machine to travel in a horizontal direction, by opening the intakes 28 and 29, the air is drawn in through the latter 75 and travels, as indicated by the arrows in Figure 3, to the chamber 46 and from there is compressed by the baffle and operated upon by the propeller blades to drive the machine.

80 Having now dealt with the operation of opening and closing the air intakes 28 and 29, I will proceed to describe the mechanism for opening and shutting the air intakes 22 and 23 which consists of shutters 85 or closure members 62 adapted to fit into these openings and provided with suitable padding 63 to make them airtight when in closed position. These closure members 62 are provided with a cross supporting bar 64 to which is connected the shaft 65 carrying at its lower and opposite end the gear 54 designed to mesh with the gear 53 on the transversely extending shaft 52 whereby, on the latter being operated, the shutters 62 90 are moved upwardly or downwardly on the guideways 66 extending vertically at each side, (see Figure 8).

95 Having regard to the foregoing, the operation of my device as already alluded to is as follows in the example of it as here shown applied to an aeroplane:—The pilot, having assumed his position and first started the engine, will operate the mechanism to cause the plane to ascend. This is done 100 by turning the operating wheel 49 to rotate the shaft 52, causing the shutters or tops 62 in the air intake openings 22 and 23 in the top of the wings to move downwardly opening the air intakes and allowing the 105 air to be sucked in under the influence of the propellers in the casing 10. The rush of air thus created by means of the propellers and the temporary vacuum formed in the chamber 46 then hits the propellers and is 110 at once in its passage through them arrested by the fixedly mounted baffle 43 on the drive shaft 16, momentarily causing the air to concentrate or become compressed before reaching the second propellers and thus, as previously explained, providing 115 concentrated or compressed air momentarily and thereby increased resistance to the action of the propeller blades whereby greater efficiency and speed is obtained with 120 a decreased number of propeller rotations. On the plane assuming a predetermined height the mechanism is further operated to close the intakes 22 and 23 and open the air intakes 28 and 29, with the result that 125 130

the air is similarly sucked in through the latter openings and the machine propelled horizontally instead of vertically.

The advantages of my improved means 5 will now be apparent in descending, when the air intakes 28 and 29 are closed and the top air intakes 22 and 23 are opened. Moreover, with the conveniences described, it would be possible to hover over a certain 10 point.

The chamber 46 has, as may be seen, the propellers so arranged as to completely extend across it forming, as it were, a back for it so that when the propellers are rotated 15 the air, after passing through them and the baffle member, will be exhausted through the open discharge at the end of the casing and around the engine, thereby automatically keeping it cool. It may be 20 advisable, instead of allowing the air to discharge horizontally, to provide means for diverting the exhaust air downwardly and then upwardly beneath the machine to assist it in raising.

25 While my invention is here shown as applied to an aeroplane, it can be adapted for a great many other purposes, such as airships, motor sleighs and cars, motor boats, river transportation, mining ventilation, life 30 saving apparatus from the shore to the ships in distress, in fact in any manner in which power is used.

As many changes could be made in the above construction, and many apparently 35 widely different embodiments of my invention, within the scope of the claims, constructed without departing from the spirit or scope thereof, it is intended that all matter contained in the accompanying specification and drawings shall be interpreted 40 as illustrative and not in a limiting sense.

What I claim as my invention is:

1. In means of the character described, a 45 casing having air intakes and discharge openings and formed with air channels, power generating means within the casing, a driving shaft for the power means, pairs of propellers keyed on said shaft and in spaced relationship to one another, a baffle 50 member rigidly mounted in the casing between the pairs of propellers, a hub for the baffle member adapted to operatively engage with said shaft, a plurality of blades forming the baffle member, a hinged rim for said 55 blades and a space between said blades corresponding to the width of a blade.

2. In means of the character described, the 60 combination with a casing having air intake and discharge openings therein and a plurality of channels of different lengths formed in said casing and communicating with the air intakes, a prime mover in the casing, a driving shaft, a plurality of propellers on said shaft arranged in pairs and 65 having spoon-shaped blades in staggered re-

lationship to one another, a baffle member rigidly mounted in the casing between the pairs of propellers and including curved blades spaced from one another at a distance equal to the width of a blade.

3. The means as described in claim 2 in which the baffle member comprises a hub adapted to operatively engage with the driving shaft, a plurality of spaced blades curved inwardly towards the hub to concentrate 70 the air pressure on the hub and a rim formed of hinged sections for the blades.

4. In means of the character described, a double casing formed with a hollow nose or head, air channels in the casing, a prime mover, a plurality of propellers, arranged in pairs in spaced relationship to one another, rotatably mounted in said casing and designed to form with the walls of the casing 80 an air chamber, a baffle member rigidly mounted in the casing, between the pairs of propellers, air intakes communicating through said channels with the air chamber, whereby on the propellers being operated 85 the air is drawn into the chamber to contact with the baffle member to be concentrated and compressed, air discharge means for the casing.

5. In aeroplanes and the like, an engine 90 provided with a casing, a driving shaft, propellers mounted in pairs on said shaft and in spaced relationship to one another and having their blades in staggered relationship, non-rotatable baffle members between 95 each pair of propellers, means for supplying air to the casing comprising channels in the casing, air conduits connecting said channels with air intake openings in the aeroplane wings, closures for said air intakes, mechanism for operating the closures 100 and an open air exhaust for the casing whereby the air is discharged on each side of the engine to cool.

6. In aeroplanes and the like and in combination with a casing for the engine, a 110 propeller shaft, a plurality of propellers mounted in pairs on said shaft, the pairs being in spaced relationship to one another and having their blades in staggered relationship, a non-rotatable baffle member between each pair of propellers, means for supplying air to the casings comprising channels formed in the casing and communicating through air conduits with air intake 115 openings in the wings of the aeroplane, closures for said air intakes, mechanism for operating the closures to raise and lower the plane and to drive it horizontally, an open air exhaust for the casing whereby the air is discharged on each side of the engine to cool.

7. The device as described in claim 6 in which the air intake openings in the wing are formed in the top and front sides of the wing respectively.

8. The device as claimed in claim 6 in which the casing is formed with channels on opposite sides thereof open at one end and adapted to engage with conduits at the 5 other end, in turn connected to the air intake openings in the top of the aeroplane wings whereby, on the closures for said intakes being opened, the plane will rise in a vertical direction.
10. 9. The device as claimed in claim 6 comprising a casing formed with channels on opposite sides thereof opening into the casing at one end and connected to the air intake openings in the wing tops at the other 15 end, channels spaced from the aforementioned channels and spaced from one another formed in said casing and opening at one end into the casing and connected through conduits at their other ends with 20 the air intake openings in the front of the wings, closures for said wing top and side air intake openings, and mechanism for simultaneously opening the top air intakes and closing the side air intakes and for 25 closing the top air intakes and opening the side air intakes simultaneously to cause the machine to rise vertically and travel horizontally.
10. An aeroplane having air intake openings in the wing tops and air intake openings in the front of the wings, an airtight casing for the engine, air conduit means in 30 said casing communicating with the wing top air intakes and the wing side air intakes respectively, a propeller shaft for the engine, a plurality of pairs of propellers on said shaft, said pairs being in spaced relationship to one another, a non-rotatable baffle member between the pairs, a plurality 35 of spaced baffle blades in said member, the space between the blades being equal to the width of a propeller blade, and the pro-
- pellers being arranged so as to cause the blades to be in staggered relationship to one another, air exhaust means for the casing, 45 closures for the air intakes, and mechanism for operating the closures whereby, when the top intakes are closed, the side air intakes are opened, and whereby, when the side air intakes are closed, the top air intakes are opened.
11. In an aeroplane, the combination with intake openings in the top of the wings, and air intake openings in the front of the wings, of an airtight casing for the engine having 50 an air chamber therein communicating with the wing top air intakes and the wing side air intakes respectively, closures for said air intakes and means for opening one set of air intakes and closing the other set of air intakes simultaneously and whereby, on the propellers and the intake closure mechanism being operated, the air is drawn in to said chamber, baffle member on the propeller shaft between said propellers whereby, on the in-sucked air passing through the first propellers, it is compressed by said baffle member before reaching the second set of propellers. 55
12. The means as described in claim 11 60 in which the baffle member is non-rotatable and arranged between pairs of propellers and in which the blades are suitably curved and provided with a hingedly jointed rim. 65
13. The combination with the means described in claim 11 in which an engine or the like is housed within the casing for operating the propellers and in which discharge means are provided in the casing to discharge the exhaust air on each side of 70 the engine to automatically cool it. 75
- In witness whereof I have hereunto set my hand.
- MAX EMILIUS MILLWOOD.
